The ornamental design for an animal tread footwear, as shown and described.

DESCRIPTION

FIG. 1 shows an elevated bottom perspective view of an animal tread footwear according to a preferred embodiment; and,

FIG. 2 shows a bottom plan view of the tread of FIG. 1. The broken lines depict portions of the animal tread footwear that form no part of the claimed design. The broken line perimeters seen within the solid line edges of the animal treads on the footwear bottom are boundaries of the claimed design. These broken lines and the areas within them also form no part of the claimed design.
